CLAIM

I claim the ornamental design for an expandable bulb-holding clip, as shown and described.

DESCRIPTION

FIG. 1 is a front perspective view of an expandable bulb-holding clip showing my new design;

FIG. 2 is a rear perspective view thereof;

FIG. 3 is a front perspective view thereof;

FIG. 4 is a rear perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a top plan view thereof; and,

FIG. 10 is a bottom plan view thereof.

The dashed lines in the figures form no part of the claimed design. All other surface(s) or portion(s) of our designs not shown in the figures or otherwise described in the specification form no part of the claimed design.
